UNITED STATES PATENT OFFICE

HENRY BURTON LOGIE, OF ROSELLE PARK, NEW JERSEY

SORTING AND PACKAGING MACHINE

Application filed November 9, 1928. Serial No. 318,252.

This invention relates to an apparatus for sorting, packaging and counting coins, and is designed and adapted to be used in commercial institutions, such as banks, where large quantities of coins are to be sorted and packed in containers in counted quantities.

The invention in its broadest aspect aims to automatically sort or segregate the coins of each denomination from a mixed collection, and then pack coins of each denomination in individual containers, packets or cartridges, with a predetermined or counted number of the coins.

One of the objects of the invention is to provide in an apparatus of the indicated character, similar packaging units, each of which handles preformed containers or cartridges, and which packs or fills each container with a similar predetermined or counted number of coins of a particular denomination, and which seals or closes each container; together with coin sorting and feeding mechanism for feeding to each unit, the coins of the same denomination, to produce the packages.

In accordance with another object of the invention use is made of a special type of coin container or cartridge, and practical and novel means adapted to readily handle each cartridge to transfer or deliver it to the coin packing or loading mechanism.

Another object is to provide an improved construction of magazine for containing and feeding the cartridges to the cartridge transferring mechanism.

Another object is to provide an improved construction of deforming mechanism for deforming each of the special coin cartridges, to seal or close the same.

Another object is to provide an improved construction of coin packing or loading mechanism, which at all times positively acts on the coins, to thereby assure proper movement of the coins in loading the containers or cartridges therefor.

Another object is the provision of an improved means which operates in conjunction with each coin container or cartridge during the loading thereof to compensate for variations in the length of the stack of coins,

due to variations in the thicknesses of the coins.

Another object is an apparatus of the indicated character, in which the several mechanisms are operated by a single source of power, and in which the operation of each mechanism in timed accord with the others, is accomplished automatically.

With the foregoing and other objects in view the invention resides in the combinations, construction, relative disposition, and operation of the parts hereinafter described and illustrated in the accompanying drawings, in which:

Fig. 1 is a general view of the apparatus embodying the features of the invention, parts being shown in section and certain parts being broken away. 65

Fig. 2 is a side view of one of the packaging units. 70

Fig. 3 is an enlarged plan view partly in section and showing certain features of one of the packaging units. 75

Fig. 4 is a view looking at the opposite side of the packaging unit shown in Fig. 2. 75

Fig. 5 is a transverse sectional view taken on the line 5—5 of Fig. 4, of the cartridge transferring mechanism showing a relationship of parts to receive a cartridge from magazine. 80

Fig. 6 is an enlarged transverse sectional view taken substantially on the line 6—6, of Fig. 2, looking in the direction indicated by the arrows. 80

Fig. 7 is a plan view partly in section of the unit shown in Figs. 2 and 4. 85

Fig. 8 is a side view of the unit shown in Fig. 7, with the parts in the same relationship. 90

Fig. 9 is a sectional view showing how a full cartridge is discharged. 90

Fig. 10 is a sectional view showing how a full cartridge is deformed to close it. 95

Fig. 11 is a sectional view showing how a coin is pushed into a cartridge. 95

Fig. 12 is a perspective view of one of the cartridges used, the cartridge being empty. 100

Fig. 13 is a perspective view of a full cartridge after leaving the apparatus. 100

Fig. 14 is a sectional view showing certain details.

Fig. 15 is an end view of the means for transferring one of the cartridges from the magazine to the coin packing mechanism.

Fig. 16 is a view similar to Fig. 5, but showing a relationship of the parts during the packing of a cartridge.

Fig. 17 is a detail sectional view of the cartridge deforming device.

Fig. 18 is a sectional view taken on the line 18—18, of Fig. 17.

Fig. 19 is a view similar to Fig. 17, but showing the crimping members moved to crimping positions.

Fig. 20 is a sectional view showing certain details of the mechanism which controls the operation of the clutch controlling mechanism, the section being taken on the line 20—20, of Fig. 21.

Fig. 21 is a side view of the parts shown in Fig. 20.

Fig. 22 is a vertical sectional view through the cartridge magazine with a supply of cartridges therein.

Fig. 23 is a sectional view taken on the line 23—23, of Fig. 22.

Fig. 24 is a horizontal sectional view taken on the line 24—24, of Fig. 23.

Fig. 25 is a vertical sectional view through the coin hopper and showing the agitating device, the section being taken on the line 25—25, of Fig. 26, looking in the direction indicated by the arrows.

Fig. 26 is a sectional view taken on the line 26—26, of Fig. 25, looking in the direction indicated by the arrows.

Fig. 27 is a sectional view taken on the line 27—27, of Fig. 28, showing the manner in which a defective or worn coin is discarded.

Fig. 28 is a side view of portions of connecting branch coin chutes shown in Fig. 27.

Fig. 29 is a side view of portions of the main coin chute and a connecting branch chute.

Fig. 30 is a diagrammatic view of the clutch and means controlled thereby.

Generally stated, the apparatus comprises the combination of a casing, in which are arranged similar units for packaging the coins, there being one unit for pennies, one for nickels, one for dimes, one for quarters, one for halves and one for dollars, each unit consisting of a coin container or cartridge magazine, cartridge transferring mechanism, cartridge packing mechanism to which the cartridge transferring mechanism delivers cartridges one at a time from the magazine, each cartridge to be packed with a predetermined or counted number of coins of the same denomination, mechanism common to all of said units for sorting or segregating the coins of each denomination from a mixed collection and then feeding the coins of the sev-

eral denominations respectively to said packing mechanisms, and coin counting mechanism.

Each of the packaging units is operated from a single source of power transmitted through a driving shaft 10 which enters the casing or housing 11, said shaft 10 being supported by suitable bearings 12 secured to the inside of one of the walls of the casing 11. The shaft 10 has a pinion 13 which meshes with a pinion 14 on a horizontally disposed driven shaft 15 supported for rotation by bearings 16. Constant rotary motion is transmitted from the shaft 15 directly to the packaging units 17.

The units 17 are identical in construction and operation, but the parts of each are made of sizes in proportion to the particular denomination of the coins to be handled and packaged by the unit. Inasmuch as each unit 17 is identical in construction and operation a description of one will suffice for all. The unit 17 includes driven shafts 18, 19 and 20.

The shaft 18 has associated therewith a duplex clutch 21 which consists of a member 22 loosely keyed to the shaft 18 for sliding movement thereon and rotation therewith, a member 23 which loosely surrounds the shaft 18 and is journaled for rotation in a fixed bearing on a pedestal 24, and a member 25 which loosely surrounds the shaft 18 and is journaled for rotation in a fixed bearing on a pedestal 26. The said pedestals 24 and 26 are secured to a suitable base 27. The shaft 18 is provided with a beveled gear 28 which meshes with a similar gear 29 on the shaft 15. It will now be understood that rotary motion is constantly transmitted to the shaft 18 by the shaft 15 through the intervention of the gears 28 and 29.

When the clutch member 22 is moved into cooperating engagement with the clutch member 23, by mechanism to be hereinafter described, rotary motion will be transmitted to a gear 30 integral with or secured to the member 23. The gear 30 meshes with a gear 31 keyed to the shaft 19. The shaft 19 is journaled for rotation in bearings respectively on the pedestals 24 and 26, and bearing respectively on pedestals 35 secured to the base 27. The shaft 19 has a mutilated gear 36 keyed thereto, the teeth of which are adapted to mesh with the teeth of a gear 37 keyed to the shaft 20. The shaft 20 is journaled for rotation in bearings respectively on pedestals 38 secured to the base 27. It will now be understood that the shaft 20 will be rotated intermittently by the shaft 19 through the intervention of the mutilated gear 36 and the gear 37. The pedestals 38 have secured thereto a rigid support 39 which is horizontally disposed.

In accordance with the invention a novel type of coin container or cartridge 45 is used and is adapted to be filled or loaded with a

130

predetermined number of coins and then be sealed or closed to constitute a package of coins of a certain denomination. The cartridge 45 is made preferably from a metal blank which is stamped, bent and formed to provide an end 46, side members 47 equally spaced, there being three in number, and said side members 47 are connected together by a ring 48. The ring 48 surrounds the member 47 in a position thereon so that the members 47 will provide projecting bendable end portions 49 respectively as shown most clearly in Fig. 12. A magazine 50 is adapted to contain a supply of cartridges 45 and to guide them for downward movement by the action of gravity to the lower discharge end of the magazine. The magazine 50 is mounted on the support 39. The magazine 50 comprises two main parts or sections 51 and 52. The sections 51 and 52 are of cross sectionally rectangular formation as best shown in Fig. 24. The section 51 is fixedly secured to or may be formed integral with the support 39 as in the present instance. The section 51 has a neck 53 and a shoulder 54. The section 52 is a removable section, and is rabbeted at the lower end in order to fit over the neck 53 and to rest on the shoulder 54 of the section 51 in vertical alinement therewith to provide a continuous chamber or space. Means is provided within the removable section 52 of the magazine engageable with two of the side members 47 of each cartridge 45 to guide it for downward movement in a predetermined position, and said means consists of a plate 55 rigidly connected with the upper end of the section 52 and disposed substantially centrally of the section 52 parallel to the opposite side walls thereof. One end wall of the lower section 51 of the magazine is provided with a discharge opening 56 which is in alinement with an opening 57 in the opposite end wall of the section 51. The lower magazine section 51 is provided with vertical guides 58 which may be secured thereto or be formed integral therewith as in the present instance. The guides 58 are disposed respectively at opposite sides of the magazine, and each is in the form of a channel and is widened at the lower end to provide a cam surface 59. Spring latches 60 are secured respectively to the opposite sides of the magazine section 52 in staggered relationship. The said latches 60 are designed and adapted to travel respectively in the guides 58. Each latch is provided with a roller 61 which is engageable with the cam surface 59 of the related guide, and in this manner the removable section 52 of the magazine is releasably held in place associated with the magazine section 51. The lower ends 62 of the latches 60 move through openings or slots 63 respectively in the side walls of the magazine sections 51 and 52. When it is desired to remove the

section 52 of the magazine it is only necessary to take hold of the upper end of the section 52 and exert an upward pulling force thereon which will cause the rollers 61 to ride on the cam surfaces 59, thereby flexing the latches 60 toward the side walls of the section 52. This will cause the ends 62 of the latches 60 to project inwardly of the section 52 and will prevent a cartridge or cartridges remaining in the section 52 from falling out of the same while it is being removed.

Mechanism is provided for transferring or delivering in succession one cartridge at a time from the magazine 50 to a cartridge packing or loading mechanism to be described. The said mechanism for transferring or delivering the cartridges includes a holder 65. The holder 65 is of hollow cylindrical construction and is adapted to receive a single cartridge 45. The holder 65 is shorter in length than the length of the cartridge, so that when the latter is inserted in the holder, the projecting end portions 49 of the cartridge will extend beyond one end of the holder. The holder 65 has a longitudinal slot 66. The cartridge transferring or delivering mechanism also includes a device 67 which is designed and adapted to receive the cartridges 45 one at a time as they fall by gravity into the section 51 of the magazine. The said device 67 is in the form of a slide guided for reciprocatory movement in guide grooves 68 respectively in the side walls of a slot 69 in the support 39. The device 67 is provided at one end with means to hold each cartridge 45 in a set position against relative turning movement, and the said means is in the form of a rigid member 70 substantially triangular in cross section and therefore engageable with the side edges respectively of two of the side members 47 of the cartridge as shown most clearly in Fig. 22. It will be apparent that the lower end of the guide plate 55 terminates above the device 67 and bears such relationship to the member 70 as to guide the lowermost cartridge 45 in position relative to the member 70. The device 67 is also provided with a pusher 71 on the end thereof opposite that having the member 70. The device 67 is provided with a pin 72 on the under side thereof which extends into a continuous cam groove 73 of a cam 74 keyed to the shaft 20. The construction and arrangement of the device 67 and the cam 74 is such that upon one-half revolution of the cam 74, the device 67 will be moved forwardly to deliver a cartridge 45 into the holder 65 when the latter is in position adjacent the discharge opening 56 in the magazine section 51. In this connection it is to be observed that the lower portion of the member 70 is accommodated by the slot 66 in the holder 65, that the pusher 71 moves through the opening 57 into contact with the end 46 of the cartridge 45 and pushes the cartridge through

the discharge opening 56 into the holder 65; and that the member 70 is spaced relatively to the pusher 71 a sufficient distance to bring the member 70 outside of the discharge end 5 of the holder 65 to allow the holder to be moved to a coin filling or loading position. It will also be apparent that when the device 67 is at the limit of its forward movement, the pusher 71 will be in a position beneath 10 the stack of cartridges 45 to hold them up. In the second half revolution of the cam 74, the device 67 will be moved rearwardly to a position to allow the next lowermost cartridge 45 to drop in place on the device 67 15 retained in proper position by the member 70 until the device 67 is again brought forward. The holder 65 is provided on the underside thereof with spaced lugs 75 having alined holes which receive a guide member 76 20 rigidly secured to the upper end of a lever 77. The guide member 76 has flat sides, and the openings in the lugs 75 conform to the cross sectional shape of the member 76 to the end that the holder 65 will be slidable on the 25 member 76 but will be prevented from rocking movement thereon. The member 76 has a head 78, and a coil spring 79 surrounds the member 76 and has one end thereof in engagement with the head 78 and the opposite end 30 thereof is in engagement with the lug 75 adjacent the head 78. The spring 79 functions automatically to bring the holder 65 in a position relative to the lever 77 that it may be brought into proper position with respect 35 to the discharge opening 56 of the magazine to receive an empty cartridge, and allows the holder 65 to be moved relatively to the lever 77 to a proper coin filling or loading position. The lever 77 includes a pivot 80 supported 40 by a bracket 81 bridging one of the pedestals 35 and one of the pedestals 38. The lower end of the lever 77 has a roller 82 which is acted upon by a cam 83 keyed to the shaft 19. A spring 84 has one end thereof connected as 45 at 85 with the lower end of the lever 77, and the opposite end thereof is connected as at 86 with the adjacent pedestal 35. The cam 83 cooperates with the roller 82 of the lever 77 to move the holder 65 back and forth between 50 the magazine 50 and the mechanism to be hereinafter described for loading the cartridge in the holder with a predetermined number of coins. The spring 84 serves to keep the roller 82 constantly in engagement 55 with the peripheral surfaces of the cam 83. The cam 83 is of such design that during substantially one-half of a revolution of the shaft 19 the holder 65 will dwell in the coin loading position, and during substantially 60 the other half revolution of the shaft 19, the holder 65 will dwell in the cartridge receiving position. These two positions of the holder 65 are shown in Figs. 5 and 16.

In order to prevent unintentional turning 65 movement of the shaft 20 which would result

in movement of the device 67 when it is in the cartridge receiving position, there is provided a disk 90, which is keyed to the shaft 20. The disk 90 is cut away to provide an arcuate surface 91 on the periphery of the 70 disk. A sector of a disk 92 is fixed to the shaft 19. The radii of the arcuate surface 91 and the sector 92 are equal. It will now be apparent that there will come a time during the rotation of the shaft 19 when the gear 36 will not be operating the gear 37, when the outer edge of the sector 92 will be in contact with the surface 91, which will prevent unintentional rotation of the shaft 20, consequently, the device 67 will not be moved from the cartridge receiving position. 75

The mechanism for packing or loading each cartridge 45 while it is held by the holder 65 in the coin receiving position consists of the means and operates in the manner presently to be described. A block 95 is fixedly mounted on the pedestals 24 and 26. The block 95 has a plunger cylinder 96 which is in alinement with a coin receiver or cylinder 97. A plunger 98 operates in the cylinder 96 and is sufficiently long and its stroke is such that it will traverse the receiver or cylinder 97. In fact, in the forward stroke or movement of the plunger 98, the outer end thereof will project beyond the outer end of 90 the receiver or cylinder 97. The plunger 98 is operated in timed accord with a coin carrier 99 which is intermittently rotatable in one direction only, for bringing coins successively to a predetermined position in the 95 receiver 97. The plunger 98 is provided with a rigidly connected depending member 100 which travels in a slot 101 in the block 95. The lower end of the member 100 is connected with the upper end of a lever 102 by a pin 105 and slot connection 103. The fulcrum or pivot 104 of the lever 102 is at the lower end thereof, and is mounted on the base 27. The lever 102 is oscillated by the employment of a pin or stud 105 on the lever 102 intermediate its ends, and this pin or stud 105 is disposed in a cam groove 106 in a cam 107 free to turn on the shaft 19. The clutch member 25 has a gear 40 which may be integral therewith or be secured thereto. The gear 40 110 meshes with an intermediate gear 41 mounted on a shaft 42 supported by bearings respectively on pedestal 26 and a pedestal 43. The gear 41 meshes with a gear 44 secured to the cam 107. When the clutch member 22 is 115 moved into cooperating engagement with the clutch member 25, rotary motion will be transmitted to the cam 107, through the intervention of the gears 40, 41 and 44, and by the provision of the groove 106 and the pin or stud 105, the lever 102 will be oscillated thereby causing reciprocation of the plunger 98, through the intervention of the pin and slot connection 103 and the member 100. The coin carrier 99 hereinbefore referred to is 120 125 130

in the form of a disk which is mounted on a horizontally disposed shaft 108 to rotate therewith, the opposite ends of the shaft 108 being journaled in suitable bearings on the block 95. The carrier disk 99 has notches 109 in the peripheral edge thereof equally spaced, there being four notches in the present instance. The carrier disk 99 is disposed transversely with respect to the longitudinal axis of the coin receiver or cylinder 97, and operates in a transverse slot 110 in the latter. The carrier disk 99 is designed to bring coins successively each to a predetermined delivery position in the coin receiver 97. Means is provided in the receiver 97 for guiding each coin during its travel out of the receiver 97 and to prevent the coin from toppling or from falling on its side. The said means consists of flat springs 111, there being three in number in the present instance. The inner end of each spring 111 is secured in a groove 112 in the inner face of the receiver 97, and the outer end of the spring is normally disposed radially inward, and projects beyond the outer end of the receiver 97 as shown most clearly in Fig. 10. In order to provide intermittent rotary movement to the shaft 108 and therefore to the carrier 99, there is provided a wheel 113 which is mounted fast on the shaft 108. The wheel 113 is provided with four laterally projecting pins 114 on one side face thereof equally spaced. The clutch member 25 carries a wiper arm or cam 115 which encounters each of the pins 114 to rotate the shaft 108, and therefore the carrier 99 a quarter of a revolution in order to bring a coin held by the carrier 99 into a delivery position in the receiver 97. This is followed immediately by the movement of the plunger 98 in a forward direction to push the coin from its notch out of the receiver 97 under the influence of the springs 111. During the outward travel of the coin, the springs 111 will assume positions respectively in the grooves 112. The wheel 113 extends in a slot 116 in the block 95, and is provided with four openings 117 equally spaced and arranged similarly to the notches 109 in the carrier 99 so that the wheel 113 will not interfere with the operation of the plunger 98. The outer end of the coin receiver 97 has fixedly mounted thereon a disk 120, the central boss or hub 121 of the disk being secured to the end of the receiver 97 in any suitable manner. The disk 120 also has a central opening 122 the wall of which is a continuation of the interior wall of the receiver 97. When the holder 65 with a cartridge therein is in position alined with the receiver 97 a device 125 operates to move the holder 65 along the guide member 76 against the action of the spring 79 to the final coin loading position, and also to hold the cartridge against movement relatively to the holder 65. The device 125 includes a cylindrical casing or barrel 126 open at one end mounted on a slide 127. A coil spring 128 is arranged within the barrel 126 and one end thereof is in contact with the closed end of the barrel, and the opposite end thereof has a disk 129 which contacts with the holder 65 and the end 46 of the cartridge therein. The slide 127 has a depending pin 130 which extends into a cam groove 131 in a cam 132 keyed to the shaft 19 to rotate therewith. The walls of the cam groove 131 are designed to cooperate with the pin 130 to move the barrel 126 toward the holder 65 to cause the disk 129 under the action of the spring 128 to impart movement to the holder 65 to the final loading position, and to hold the holder 65 in this position until the cartridge therein is loaded with a predetermined number of coins. The spring 128 compensates for variations in the length of the stack of coins due to variations in the thicknesses of the coins themselves. When the holder 65 is in the loading position, the projecting end portions 49 of the cartridge 45 will be disposed between the spring 111 respectively and the wall of the opening 122 of the disk 120, said wall being provided with niches or recesses 133 to receive the end portions 49 respectively when the outer ends of the springs 111 are flexed outwardly to allow the discharge of a coin from the receiver 97 into the cartridge 45. It will therefore be understood that the springs 111 prevent each coin during its travel from the receiver 97 into the cartridge 45 from encountering and bending the end portions 49 of the cartridges in the holder 65 and also prevent each coin when it is in the cartridge from moving or toppling toward the receiver 97. A device 135 serves to prevent the coins in the cartridge from toppling, or falling towards the end 46 of the cartridge on their sides during the loading operation. The device 135 includes rods 136 supported by a bracket 137 fixedly mounted on a slide 138 guided for movement by a combined guide and support 139 fixedly attached to the pedestals 35. The rods 136 extend through the end wall of the barrel 126 and are guided and steadied thereby, and also extend through the coil spring 128 and the disk 129. The free ends of the rods 136 are constantly in contact with the innermost or the first coin delivered into the cartridge. The slide 138 is provided with a longitudinal slot 140 through which the pin 130 of the device 125 extends, and the said pin 130 also extends through a slot 141 in the support 139. The slide 138 has a depending pin 142 which extends through the slot 141 into a cam groove 143 in the cam 132. The slide 127 is supported by and has guided sliding movement relatively to the slide 138. During the first half revolution of the cam 132 both devices 125 and 135 are operated to perform their respective functions. There is a dwell in the

movement of the cam 132 after the holder 65 and the empty cartridge therein is in the loading position, and until the empty cartridge is fully loaded with a predetermined number 5 of coins. During the loading of the cartridge with coins, the coins under the action of the plunger 98 gradually push the rods 136 to return the device 135 nearly to its original position against the friction of the parts 10 thereof; the cam groove 143 in which the pin 142 operates being provided with a straight section 144 parallel to the longitudinal axis of the cam to permit the return movement of the device 135. In the continued 15 rotation of the cam 132 to complete one revolution in response to the rotation of the shaft 19, the device 125 is returned to its original position, and the device 135 will be fully returned to the original position.

20 Mechanism is provided for deforming, bending or crimping the projecting end portions 49 of the cartridge, after it has been loaded with a predetermined number of coins, to seal or close the cartridge to complete a packaging operation. The said deforming mechanism includes the disk 120 and a disk 150 rotatably mounted on the boss 121, the said disk 150 being held in place by a nut 151 screwed on the boss 121. The disk 150 25 is arranged contiguous the disk 120. Crimpers 152 are associated with the disk 120, there being three in number, and are disposed radially with respect to the disk 150 spaced equidistantly. Each crimper is guided for 30 radial inward and outward movement in a slot 153 in the disk 120. Each crimper 152 has a stud 154 which is disposed in a curved slot 155, in the rotatable disk 150. The rotatable disk 150 is provided with cams 156 35 and 157. Arms 158 and 159 are secured to the shaft 19 side by side, and are disposed diametrically opposite each other on the shaft 19. The outer end of the arm 158 has a roller 160, and the outer end of the arm 40 159 has a roller 161. During the rotation of the shaft 19, the roller 160 on the arm 158 encounters the cam 156 and causes rotatory movement of the disk 150 in one direction. This will cause the walls of the slots 155 to 45 act on the studs 154 respectively causing the crimpers 152 to move radially inward. The movement of the crimpers 152 radially inward will crimp the end portions 49, or in other words will bend the end portions 49 50 inwardly over the outermost coin in the cartridge 45, as shown most clearly in Fig. 13. This constitutes the cartridge closing or sealing operation. In the continued rotation of the shaft 19, the roller 161 on the arm 159 55 will encounter the cam 157 which has been brought to a position to be so encountered. The roller 161 acting on the cam 157 causes rotatory movement of the disk 150 in a direction opposite that previously mentioned 60 65 thereby causing the walls of the slots 155 to

act respectively on the studs 154, to move the crimpers 152 radially outward to their original positions. The operation of the deforming mechanism is in timed accord with the cartridge packing or loading mechanism. After the cartridge has been sealed or closed by crimping or bending the end portions 49, the holder 65 together with the loaded or full cartridge are moved from the loading position to a position adjacent the discharge opening 56 in the lower magazine section 51. This is followed immediately by the operation of the device 67 whose member 70 ejects the loaded cartridge 45 from the holder 65 into a discharge chute 162, and at the same time an empty cartridge 45 is pushed into the holder 65 by the pusher 71 of the device 67. Each loaded cartridge will be delivered by the chute 162 to a suitable receptacle from which they may be readily removed.

75 The coin counting mechanism operates a control mechanism which controls the operation of the clutch 21, which in turn controls the operation of the shaft 19 on which the cam 132 is mounted, and also the operation of the cam 107. It will therefore be understood that when the shaft 19 is in operation the cartridge holder 65 will be operated to transfer an empty cartridge from the magazine 80 85 90 95 100 105 110 115 120 125 130 one end connected as at 171 with the pawl 168 and the opposite end thereof is connected as at 172 with the block 95. A shaft 173 having a vertical axis is mounted on the block 95 and extends through a slot 174 in the pawl 168 to allow the latter to have pivotal and longitudinal movement. The pawl 168 has a lug 175. A spring 176 has one end thereof connected as at 177 with one end of the lever 166, and the opposite end of the spring is connected as at 178 with the nut 151. The opposite end of the lever 166 has connected therewith a pawl 179 by a pin and slot connection 180, and said pawl is also connected with the block 95 by a pin and slot connection 181 to allow pivotal and longitudinal movement of the pawl. A spring 182 has one end thereof connected as at 183 with the pawl 177, and the opposite end of the spring is connected as at 184 with the block 95. The pawl 179 is provided with a lug 185. A ratchet wheel 186 is secured to the shaft 173 to cause it to rotate therewith, and said ratchet wheel is rotated in one direction by the coaction of the lugs 175 and 185 and the teeth of the ratchet wheel in response to the movement of the pawls 168 and 179 and the levers 165 and 166, when the cam portions 167 of the latter are acted upon by a coin. The number of teeth which the ratchet wheel 186 will have depends upon the number of coins to be delivered into each cartridge 45, and in the present instance there are twenty-five teeth. When the levers 165 and 166 are brought to their normal positions by the action of the springs 170, 176 and 182, the cam portions 167 will project into the interior of the coin receiver 97, in order to be in the path of travel of each coin, and therefore the plunger 98 will be provided with grooves 187 at points diametrically opposite each other to accommodate the portions 167. The ratchet wheel 186 is rotated in the direction indicated by the arrow in Fig. 3, and is prevented from rotating in an opposite direction by a spring dog 188 mounted on the block 95. The ratchet wheel 186 has secured thereto on the upper face a cam 189. Upon the completion of one revolution of the ratchet wheel 186, the cam 189 actuates the clutch control mechanism.

The clutch control mechanism comprises the means and operates in a manner presently to be described. A device 190 is mounted on a traveler 191 guided for sliding movement on a guide member 192 formed integral with or secured to the block 95. The guide member 192 is of dovetail cross section and fits in a corresponding groove in the traveler 191. The device 190 comprises cooperating members 193 and 194, each connected with the traveler 191 for pivotal movement. The members 193 and 194 are under the influence of a coil spring 195 the opposite ends of which are connected respectively with said members. The spring 195 serves to bring the members 193 and 194 into engagement with each other. The member 193 is provided with a depending pin 196, and is also provided with a shoulder 197 which is engageable with a stop 198 on the traveler 191. An adjustable stop 199 on the block 95 is adapted to be engaged by the member 194. As the last coin is being delivered into the cartridge, the counting mechanism will be operated causing the cam 189 to move the member 193 to the position shown in Fig. 3, in which its pin 196 will be in the path of travel of a lug 200 carried by the plunger 98, the lug extending upwardly through a slot in the plunger cylinder 96. The members 193 and 194 will be in engagement with each other. During the return movement of the plunger 98 after having delivered the last coin into the cartridge, the lug 200 will encounter the pin 196, and as a consequence the traveler 191 will be slid in the direction indicated by the arrow in Fig. 3. This will cause the member 194 to encounter the stop 199 and said member 194 will move on its pivot to allow relative movement of the member 193 to a position in which the shoulder 197 will be in engagement with the stop 198, and with its pin 196 out of the path of travel of the lug 200. A member 201 is pivotally connected at one end, as at 202 with the traveler 191. When the traveler 191 is in one position, the member 201 will rest in a downwardly inclined position on the wall of an opening 203 in the pedestal 24. When the traveler 191 is moved to its other position through the intervention of the members 193 and 194, and the lug 200, the free end of the member 201 will be first acted upon by the wall 204 of an elliptical cam groove in one side face of the gear 31 which will move the member 201 upwardly to a position shown in full lines in Fig. 21, in response to the rotation of the gear 31. In the continued rotation of the gear 31, the free end of the member 201 will be acted upon by a cam surface 205 in said cam groove, which will cause the traveler 191 to move in the direction indicated by the arrow in Fig. 21. This will allow the member 194 to re-engage the member 193, by reason of the fact that the member 194 will be moved out of contact with the stop 199, and by reason of the action of the spring 195, when the member 193 is again acted upon by the cam 189 on the ratchet wheel 186. A rocker 206 is carried by the block 95 and is under the influence of a spring 207 having one end thereof connected with the rocker 206, and the opposite end being connected with the traveler 191. The rocker 206 is provided on the under side thereof with a pointed cam 208. A yoke 209 is pivotally mounted as at 210 on the pedestal 43, and is also pivotally connected with the clutch member 22. The yoke 209 is provided with an upstanding arm 211 having a stud 212 disposed in a slot 213 in the traveler 191.

The upper end of the arm 211 is in the form of a pointed cam 214 which coacts with the cam 208 on the rocker 206. It will now be understood that when the traveler 191 is moved in one direction, after each cartridge has been loaded with the predetermined or counted number of coins, the yoke arm 211 will be disposed in a position to permit the rocker cam 208 to act on the cam 214, to there-
10 by move the yoke 209 which will cause the clutch member 22 to cooperate with the clutch member 23. This will cause the shaft 19 to rotate, to carry out the operation of the cartridge deforming mechanism, and also
15 the cartridge transferring mechanism, for the purpose of discharging the loaded cartridge and for bringing an empty cartridge into the coin loading position. These mechanisms are operated by one revolution of gear 31 and
20 shaft 19. When the traveler 191 is moved in the opposite direction by the action of the cam surfaces 204 and 205 on the member 201, the yoke arm 211 will be moved to a position to permit the coaction of the cams 208 and
25 214, to move the clutch member 22 into cooperating engagement with the clutch member 25, which will cause the operation of the cam 107 causing the latter to operate the coin packing or loading mechanism for the ob-
30 vious purpose.

Mechanism is provided for sorting or segregating the coins in each denomination from a mixed collection, and for distributing coins of the same denomination to each one of the
35 units 17. The said mechanism is also designed to discard defective and foreign coins. The said mechanism is supported by the casing or housing 11 and includes a hopper 220 on the top of the casing. The hopper receives
40 the mixed collection of coins of different denominations. A main coin chute 221 is connected at one end with the discharge opening at the bottom of the hopper 220. A device is provided to agitate the coins in the
45 hopper 220 to prevent them from becoming jammed, and so that they will feed properly into the chute 221. The said device includes a pivotally mounted agitator 222 operated by a grooved cam 223, there being an arm
50 224 on the agitator, and said arm having a pin 225 disposed in the groove 226 in the cam to be acted upon by the walls thereof to cause the pivotal movement of the agitator 222 in response to the rotation of the cam 223.
55 The cam is mounted for rotation on a shaft 227 supported by suitable bearings secured to the housing 11. A bevel gear 228 on the shaft 227 meshes with a similar gear 229 on the shaft
60 10 from which motion is derived. The chute 221 is inclined downwardly and is large enough to accommodate the largest coins. At intervals in its length, the chute 221 is provided with openings 230 in one of the side walls thereof. The chute 221 inclines later-
65 ally in order to allow the coins to fall later-

ally out of their intended openings 230; it being understood that there is one opening 230 to allow the passage of coins only of the same or substantially the same size. The openings 230 occur in one of the side walls of the chute 221 to allow dimes, pennies, nickles, quarters, and halves to pass out of the chute through the openings 230 in the order named. It will therefore be understood that the openings 230 will be of various sizes, and each will be somewhat smaller as to height than the diameter of the particular coin it is intended to allow to pass. The bottom 231 of the chute has an upstanding edge 232 which bounds the related opening. The end of the chute 221 remote from the hopper terminates at the coin carrier 99 of the unit 17 which packages the dollar coins. Intermediate inclined chutes 233 communicate with the openings 230 respectively by vertical sections 234 of the chutes 233. Each of the chutes 233 terminates at the coin carrier 99 of the related packaging unit 17. Each chute 233 is substantially similar in construction to the construction of the chute 221 except that the bottom 235 thereof has a groove 236 in which defective or relatively thin coins will travel and therefore be discarded by falling through the related opening 237 into a vertical chute section 238 communicating at the upper end with the opening 237 and at its lower end with an inclined discharge chute 239 which leads to a suitable receptacle 240 for the discarded coins. The last vertical chute section 238 connects directly with the chute 239.

Each intermediate chute 233 is provided with means for checking each coin during its travel therein while the related coin carrier 99 is in motion and operates to allow the checked coin to pass from the chute into one of the notches in the carrier 99, when the latter is stopped. The said means consists of a spring device 241 attached to the chute and having a coin engaging finger which enters the chute in the path of the coin when pressure is exerted thereon by one of a series of four laterally extending cam pins 242 on the wheel 113. When the cam pin is removed the device 241 will function automatically to move the finger out of the path of travel of the coin and allow it to pass from the chute 233 into the notch of the carrier 99. Unintentional movement of the coin carrier 99 is prevented by the coaction of each cam pin 242 and portions of the device 241, it being understood that each pin 242 comes to rest between said portions after the wheel 113 has been moved by the cam arm 115.

A suitable odometer for keeping a tally of the number of coins fed into the cartridges by each unit 17 is connected with and operated by the shaft 173 of each unit 17, and such odometer is disposed at the top of the casing 11 to be readily observed. The odometer is conventionally illustrated and is des-

ignated 243. It is to be understood that coins of the same denomination may be fed to each of the units 17 without first passing through a sorting mechanism such as the one described

5 herein. It is also to be understood that the apparatus may be used for sorting and packaging other objects, tokens and coin shaped elements.

The operation of the machine herein-
10 after described is devoted to one of the coin packaging units 17. One container or cartridge 45 at a time moves by gravity onto the device 67. The device 67 is moved in one direction carrying with it the cartridge 45 and

15 delivers it into the holder 65. The holder 65 with the cartridge 45 therein is then moved or swung by lever 77 into alinement with the cylinder 97, whereupon the device 125 moves the holder 65 with the cartridge 45 therein

20 into the loading position. Meanwhile the device 67 is returned to the cartridge receiving position, whereupon another cartridge drops onto the device 67. The cartridge 45 in the holder 65 after being brought into the load-

25 ing position with respect to the cylinder 97 is filled or loaded with a predetermined number of coins. This is accomplished by the plunger 98 which operates in the cylinder 97 in timed accord with the intermittent rotation of the coin carrier 99. One coin at a time is pushed from the carrier 99 by the plunger 98 outwardly through the cylinder 97 into the cartridge 45 in the holder 65. The coins on being delivered into the cartridge through

30 the cylinder 97 operate the counting mechanism, the latter operating the control mechanism which operates the clutch 21. The clutch 21 will be operated after twenty-five coins have been delivered into the cartridge

40 stopping the operation of the coin packaging or loading mechanism and causing the operation of the mechanism for deforming, bending or crimping the projecting end portions 49 of the cartridge to close or seal the

45 same to complete the packaging operation. After the cartridge has been sealed or closed, the holder 65 together with the loaded and sealed cartridge 45 is moved by the lever 77 to a position adjacent the discharge opening

50 56 in the lower magazine section 51. This is followed immediately by the operation of the device 67 which discharges the loaded cartridge 45 from the holder 65 into the chute 162, and at the same time delivers another

55 empty cartridge 45 into the holder 65. The cycle of operation just described is repeated until the machine is stopped. It is understood of course that the coins are delivered or fed to the carrier by the sorting mechanism. The number of coins fed into the cartridges are counted and are tallied by the mechanism provided for that purpose.

60 It is to be understood that the invention is not restricted to the precise arrangement of parts shown and described, as details of

construction may be modified and rearranged without departing from the spirit of the invention, the scope of which is limited only by the terms of the appended claims.

I claim:

1. In an apparatus for packaging coins, the combination of a coin cartridge delivering mechanism, a holder adapted to receive and hold in coin loading position each cartridge delivered thereto by said delivering mechanism, a coin receiver, means to move the holder into alinement and engagement with the receiver so that the cartridge will be disposed to receive coins delivered from the receiver, means to feed one coin at a time into the receiver, means to deliver each coin from the receiver into the cartridge, means which operates after a predetermined number of coins have been delivered to the cartridge to close the cartridge by deforming it, and means which operates to eject the full cartridge from the holder after the cartridge has been closed.

2. In an apparatus for packaging coins, the combination of a magazine adapted to contain a plurality of coin cartridges, said magazine having means for guiding the cartridges during downward movement thereof, and a device for discharging one cartridge at a time at regular intervals from the magazine, said device including means engageable with the cartridge to prevent relative turning movement of the cartridge.

3. In an apparatus for packaging coins, the combination of a coin cartridge delivering mechanism, a holder adapted to receive and hold in coin loading position each cartridge delivered thereto by said delivering mechanism, a coin receiver, means to move the holder into alinement and engagement with the receiver so that the cartridge will be disposed to receive coins delivered from the receiver, means to feed one coin at a time into the receiver, means to deliver each coin from the receiver into the cartridge, means which operates after a predetermined number of coins have been delivered to the cartridge to close the cartridge by deforming it, means which operates to eject the full cartridge from the holder after the cartridge has been closed, and mechanism adapted to receive the loaded cartridges from said holder to deliver them one at a time to a disposal point.

4. In an apparatus for sorting and packaging coins, the combination of a magazine containing a supply of cartridges, a relatively fixed coin receiver, a coin carrier intermittently rotating in one direction only, for bringing coins successively to a predetermined position in said receiver, mechanism for transferring cartridges successively from the magazine to a coin loading position adjacent said receiver, means to operate the coin carrier, means to force one coin at a time

from the carrier through the receiver into each cartridge to load the latter, mechanism to deform portions of each cartridge to complete the packaging operation, and means for feeding coins to said carrier.

5. In an apparatus of the class described, the combination of a coin receiver, cartridge delivering mechanism to bring one cartridge at a time into a loading position with respect to the coin receiver to be loaded with coins, a coin carrier for bringing coins successively to a predetermined position in said receiver, a plunger operable in the receiver to force each coin from the carrier into the cartridge, each coin being guided by means in the receiver, mechanism to operate the carrier and the plunger in timed accord to load the cartridge with a predetermined number of coins, and mechanism to deform portions 20 of the cartridge after it has been loaded to complete the packaging operation.

6. In a coin packaging apparatus, the combination of coin loading mechanism, transferring mechanism for delivering one coin container at a time to the loading mechanism to be loaded with coins, counting mechanism operated by the coins as they are being loaded into each container, a constantly rotating shaft, a clutch, control mechanism, mechanism for deforming each container to complete a packaging operation, said control mechanism being operated first by the counting mechanism and then by the loading mechanism to operate the clutch, to stop the operation of the loading mechanism, and to subsequently operate the deforming mechanism.

7. In a packaging apparatus, the combination of a magazine containing a supply of similar containers each adapted to be loaded or filled, said magazine having a discharge opening, said magazine having provision to hold all containers similarly disposed during their travel to the discharge opening, a device adapted to receive the containers one at a time and discharge them successively through said discharge opening, and a holder mounted for movement into and out of registry with said discharge opening, in timed accord with the operation of said device, for the purpose of transferring the containers one at a time to a loading position.

8. In a packaging apparatus, the combination of a magazine containing a supply of similar containers each adapted to be loaded or filled, said magazine having a discharge opening, said magazine having provision to hold all containers similarly disposed during their travel to the discharge opening, a device adapted to receive the containers one at a time and discharge them successively through said discharge opening, a holder mounted for movement into and out of registry with said discharge opening, in timed

accord with the operation of said device, for the purpose of transferring the containers one at a time to a loading position, an intermittently rotatable shaft, a cam on said shaft to operate said device, a lever on which the holder is mounted for movement into and out of registry with said discharge opening, a cam on said shaft to operate the lever to move the holder out of registry with the discharge opening into a loading position, and means acting on the lever to move the holder out of the loading position into registry with the discharge opening.

9. In a coin packaging apparatus, the combination of a movable holder adapted to hold a coin container adapted to be loaded with coins, a device mounted for movement into position with respect to the holder, said device including means engageable with one end of the container, and also one end of the holder, said means being yieldable to allow movement of the holder, for the purpose of compensating for variations in the length of the stack of coins in the container, due to variations in the thicknesses of the coins.

10. In a coin packaging apparatus, the combination of a movable holder adapted to hold a coin container adapted to be loaded with coins, a device mounted for movement into position with respect to the holder, said device including means engageable with one end of the container, and also one end of the holder, said means being yieldable to allow movement of the holder, for the purpose of compensating for variations in the length of the stack of coins in the container, due to variations in the thicknesses of the coins, and a device mounted for movement into position with respect to the holder to keep the coins in the container from toppling.

11. In apparatus of the class described, a magazine adapted to contain a supply of article holding containers, said magazine comprising a relatively fixed section and a removable section, said fixed section having a discharge opening, means in the removable section adapted to guide the containers for downward movement toward the discharge opening, means to releasably hold the removable section associated with the fixed section, said last means consisting of spring catches having end portions which may extend in registered holes in said sections, cam rollers on the catches, and cams on the fixed section which coact with said rollers to flex said catches to bring their end portions into inwardly projected positions in relation to said removable sections.

12. In an apparatus of the class described, the combination of a magazine adapted to contain a plurality of cartridges having downward movement, said magazine having an opening in the bottom thereof, a device for discharging one cartridge at a time at regular intervals from the magazine, said

device comprising a member having intermittent movement alternately in opposite directions in relation to said opening and on which the cartridge may rest, means to prevent the cartridge from turning, means to push on one end of the cartridge, and means to operate said member.

13. In an apparatus of the class described, the combination of a magazine adapted to contain a plurality of cartridges having downward movement, said magazine having an opening in the bottom thereof, a device for discharging one cartridge at a time at regular intervals from the magazine, said device comprising a member having intermittent movement alternately in opposite directions in relation to said opening and on which the cartridge may rest, means on the forward end of said member to prevent the cartridge from turning, means to push on one end of the cartridge, and means to operate said member.

14. In an apparatus of the class described, the combination of a magazine adapted to contain a plurality of cartridges having downward movement, said magazine having an opening in the bottom thereof, a device for discharging one cartridge at a time at regular intervals from the magazine, said device comprising a member having intermittent movement alternately in opposite directions in relation to said opening and on which the cartridge may rest, means to prevent the cartridge from turning, means on the rear end of said member to push on one end of the cartridge, and means to operate said member.

15. In an apparatus of the class described, the combination of a magazine adapted to contain a plurality of cartridges having downward movement, said magazine having an opening in the bottom thereof, a device for discharging one cartridge at a time at regular intervals from the magazine, said device comprising a member having intermittent movement alternately in opposite directions in relation to said opening and on which the cartridge may rest, means to prevent the cartridge from turning, means on the rear end of said member to push on one end of the cartridge, and also to hold the cartridge in the magazine from moving downwardly while said member is in motion, and means to operate said member.

16. In an apparatus of the class described, the combination of a magazine adapted to contain a plurality of cartridges having downward movement, said magazine having an opening in the bottom thereof, a device for discharging one cartridge at a time at regular intervals from the magazine, said device comprising a member having intermittent movement alternately in opposite directions in relation to said opening and on which the cartridge may rest, means on the

top of said member to prevent the cartridge from turning, means on the rear end of said member to push on one end of the cartridge, and means to operate said member.

17. In an apparatus of the class described, the combination of a magazine adapted to contain a plurality of cartridges or containers having movement under the action of gravity, said magazine having an opening in the bottom thereof, a tubular holder movable into and out of registry with said opening, said holder having a slot extending longitudinally therethrough, a device for discharging one cartridge at a time from the magazine into said holder when the latter is in registry with said opening, said device comprising a member having intermittent movement alternately in opposite directions and on which the cartridge may rest, means on the top of the forward end of said member to prevent the cartridge from turning and adapted to travel through said tubular member and its slot, means on the rear end of said member to push on one end of the cartridge, and means to operate said member.

18. In an apparatus of the class described, the combination of an arm having oscillatory movement, a tubular holder, means mounting the holder on the arm for axial movement, and means constantly acting on the holder to yieldingly hold it in a predetermined position in relation to said arm.

19. In an apparatus of the class described, the combination of an oscillatory arm, a rigid member rigidly secured to the outer end of said arm, a tubular holder having lugs, said rigid member extending loosely through said lugs so that said holder may have axial movement, and means carried by said rigid member and constantly acting on one of said lugs to temporarily hold the holder in a predetermined position in relation to said arm but allowing the holder to be moved out of said position.
